(57) **CLAIM**

The ornamental design for a faceted reflector assembly, as shown.

DESCRIPTION

FIG. 1 is a perspective view of a faceted reflector assembly of our new design;

FIG. 2 is a front elevational view of the reflector assembly of FIG. 1;

FIG. 3 is a bottom plan view of the reflector assembly of FIG. 1;

FIG. 4 is a top plan view of the reflector assembly of FIG. 1;

FIG. 5 is a perspective view of a first alternative embodiment of a reflector assembly;

FIG. 6 is a front elevational view of the reflector assembly of FIG. 5;

FIG. 7 is a bottom plan view of the reflector assembly of FIG. 5; and,

FIG. 8 is a top plan view of the reflector assembly of FIG. 5.
